UNITED STATES PATENT OFFICE.

WILLIAM ELMER TURNER, OF TOPPENISH, WASHINGTON.

VALVE-GRINDER.

Specification of Letters Patent. Patented Feb. 27, 1917.

1,217,669.

Application filed June 13, 1916. Serial No. 103,544.

To all whom it may concern:

Be it known that I, WILLIAM ELMER TURNER, a citizen of the United States, residing at Toppenish, in the county of Yakima and State of Washington, have invented certain new and useful Improvements in Valve-Grinders; and I do hereby declare the following to be a full, clear, and exact description of the invention, such as will enable others skilled in the art to which it appertains to make and use the same.

My invention relates to new and useful improvements in valve grinders and more particularly to that class wherein cage valves are used, and my object is to provide a chuck for gripping the stem of the valve and supporting the valve and the cage thereon.

A further object is to provide means for imparting a reciprocating rotary movement to said chuck.

A further object is to provide means for intermittently reversing the rotation of the chuck whereby the cage will be caused to rotate independently of the valve and chuck.

And a further object is to provide suitable adjusting means for parts of the grinding device.

Other objects and advantages will be hereinafter set forth and more particularly pointed out in the accompanying specification.

In the accompanying drawings which are made a part of this application,

Figure 1 is a side elevation of the grinder showing a valve and cage in operative relation therewith, a part of the cage and valve being broken away.

Fig. 2 is a top plan view of the grinding device, and

Fig. 3 is a detail elevation of the idlers employed for guiding the driving belt of the grinder.

Referring to the drawings in which similar reference numerals designate corresponding parts throughout the several views, 1 indicating a standard having at one end a supporting base 2 by means of which the standard may be readily secured to any suitable form of support, such as a work bench, or the like.

Attached to the upper portion of the standard is a bracket 3, which is adjustably mounted on the standard 1 and held in its adjusted position by means of a set screw 4, said bracket having a pair of arms 5 through which is rotatably mounted a shaft

6, having at its lower end any suitable form of chuck 7. The shaft 6 is to be rotated alternately in reverse movement so that the valve 8, the stem 9 of which is secured in the chuck 7, will be likewise rotated; while the valve cage 10, seated and resting upon said valve, will also be given a reciprocating rotary movement by the momentum of the valve 8 to cause the cage 10 to move relatively to the valve, thereby more truly grinding the seats 11 and 12, between the valve and valve cage respectively, this reciprocating rotary motion being imparted to the shaft 6 by attaching a lever 13 to the upper end of the shaft 6, said lever being pivotally attached to one end of a pitman 14 through the medium of a bolt 15, said lever having a plurality of openings 16, whereby the swinging movement of the lever may be increased or decreased.

The opposite end of the pitman 14 is attached to a wrist pin 17, carried by a pulley 18 mounted upon a shaft 18' extending upwardly from the bracket, said shaft being so positioned that the bracket may be moved upwardly and downwardly without the pulley coming in contact with the standard, said pulley 18 being of the step down variety or having a plurality of belt engaging faces of different diameters, whereby the speed of the pulley may be increased or decreased as occasion may require. Coöoperating with the pulley 18 is a belt 19, which extends from the pulley 18 to a pulley 20, of a motor 21, said motor being preferably of the electric type, although other forms of motor may be used, if desired, and in order to hold the belt in proper alignment with the pulleys 18 and 20, the pulley 18 resting in a horizontal position, while the pulley 20 rests in a vertical position, idler sheaves 22 are mounted upon a shaft 23 carried by a frame 24, said sheaves being adjustable longitudinally of the shaft, through the medium of collars 25, thereby positioning the sheaves to correspond with the diameters of the various faces of the step down pulley. The frame 24 is provided with an elongated slot 26 through which extends a bolt 27 carried by the bracket 3, said bolt having a nut 28 thereon for locking the frame in fixed relation with the bracket, and by providing the elongated slot, the frame and idler sheaves may be moved upwardly and downwardly as desired.

In operation, a quantity of grinding substance or compound is placed upon the valve

and valve seat within the cage at the points where they are to be ground, and the stem of the valve then secured in the chuck 7. The motor is then started, which will result 5 in rotating the pulley 18 in one direction, while the pitman 14 will move the lever 13 backwardly and forwardly in the arc of a circle, thus imparting a rocking motion to the shaft 6, rotating the valve 8 a predetermined distance in one direction and then 10 reversing the rotation thereof for a predetermined distance in the opposite direction. As the cage 10 simply rests upon the valve 8 by its own weight in such manner that 15 the seats of the cage and valve will register with each other, the momentum imparted to the cage, by the first rotation of the shaft 6, will continue the rotation of the cage in the same direction, even when the rotation 20 of the valve is reversed, thereby setting up a relative movement or grinding action between the seats of the cage and valve.

In view of the fact that the valve cage 25 travels slowly first in one direction then in the other while the valve travels rapidly in the opposite directions, the grinding operation may be quickly performed and the seats will be ground perfectly true so as to properly hold compression.

It will likewise be seen that in view of the rapidity at which the valves may be ground, a greater number of valves may be ground at a minimum expense and in a minimum space of time.

35 I claim:—

1. A valve grinder comprising a vertically disposed shaft, a chuck carried by the lower end of the shaft adapted to support a valve and a valve cage seated loosely upon the valve, means arranged above the shaft to impart a rotary reciprocating movement to

said shaft whereby the valve will be caused to rotate back and forth and the cage to move relatively to the valve.

2. A valve grinder comprising a vertically disposed shaft, a chuck carried by the lower end of the shaft and adapted to support a valve and a valve cage seated loosely upon the valve, a lever attached to the upper end of said shaft, and means to swing said lever back and forth whereby the shaft and valve will be oscillated and the cage thereby caused to move relatively to the valve.

3. In a valve grinder, the combination 55 with a shaft, and means to attach a valve and cage to said shaft, of a lever attached to said shaft, a pitman adjustably attached at one end to said lever, a stepped pulley, a wrist pin on said pulley to which the opposite end of said pitman is attached, and means to rotate said pulley whereby the lever will be swung back and forth in the arc of a circle and the shaft and valve attached thereto oscillated and the cage caused to 60 oscillate relative to the valve.

4. In a valve grinding device, a standard, a bracket adjustably mounted upon said standard, a valve carrying shaft mounted in said bracket, a stepped pulley carried by said bracket, a pitman attached to said pulley, a lever attached to said shaft, means to adjustably secure the pitman to the lever, a driving belt coöperating with said pulley, and adjustably mounted idler sheaves adapted to guide the belt on to said pulley.

65 In testimony whereof I have signed my name to this specification in the presence of two subscribing witnesses.

WILLIAM ELMER TURNER.
